UNITED STATES PATENT OFFICE.

RUDOLF STRAUBEL, OF JENA, GERMANY, ASSIGNOR TO THE FIRM OF CARL ZEISS, OF JENA, GERMANY.

DOUBLE TELESCOPE WITH SUPPORT.

No. 873,105.

Specification of Letters Patent.

Patented Dec. 10, 1907.

Application filed January 25, 1907. Serial No. 353,981.

To all whom it may concern:

Be it known that I, Professor RUDOLF STRAUBEL, doctor of philosophy, a citizen of the German Empire, and residing at Carl-Zeissstrasse, Jena, in the Grand Duchy of Saxe-Weimar, Germany, have invented a new and useful Double Telescope with Supports, of which the following is a specification.

- 10 The invention consists in an improved connection of the larger hinged double telescopes with their supports, under which term is to be understood a handle, the head of a stand and the like, without prejudice as 15 to whether this support be permanently fixed to the telescope or not. The connection hitherto employed between the two consisted in the hinge-bolt of the double telescope being clutched with more or less friction 20 in a bearing of the support. Since in hinged double telescopes without exception the adaptation of the distance between the oculars to the inter-pupillary distance of each observer has to be effected by enlarging 25 or diminishing the angle which the single telescopes make with one another, and further since the double telescope has to sit symmetrically upon its support for convenient use, in order that in the vertical position of the 30 support both oculars lie at the same level, it follows, that in altering the distance between the oculars even in the most favorable construction—that is, when neither single telescope is rigidly connected with the hinge-bolt—care and dexterity are requisite to effect the alteration, so that the new position 35 of the double telescope is once more a symmetrical one.

Through the present invention the user of 40 a hinged double telescope having a support, is absolved from the necessity of paying attention to the symmetrical trim of the instrument relative to its support. This is accomplished by the two single telescopes 45 being guided symmetrically upon the support, so that, during the adaptation of the distance between the oculars to the inter-pupillary distance, the plane of the axes of the oculars undergoes vertical displacement 50 merely, but no rotation. Such symmetrical

guiding of the single telescopes relatively to the support is, in general, independent of the means adapted to secure the angle as adjusted between the single telescopes, whether merely friction of the joint sufficient for the 55 purpose or a special mechanical arrangement be used as such means.

In some cases, it may be expedient to form the device for the symmetrical guiding of the single telescopes relatively to the support also as an operating contrivance, by means of which the diminishing or enlarging of the angle between the single telescopes is effected. The operating contrivance can in that case be developed, so that, at the same 65 time, it secures the angle as adjusted.

If the guiding device be coupled with a spring instead of developing it as an operating contrivance then the alteration of the angle between the single telescopes has to be 70 again proceeded with by rotating these telescopes by hand; the spring can, however, of itself alone or in coöperation with the resistance offered by friction, for instance, the friction of the hinge, serve the purpose of securing the angle as adjusted. The spring can be easily arranged, so that its tension grows, as the tendency of the single telescopes to rotate about their common hinge increases, and, inversely, so that the spring 75 tension becomes less, as the moment of the weight of each single telescope decreases.

In the annexed drawings: Figure 1 is the front view of a hinged double telescope and its support, the two single telescopes being 80 guided upon and symmetrically to the support. Fig. 2 is a section along line 2—2 in Fig. 1, shown on an enlarged scale. Fig. 3 is the front view of a similar combination. Fig. 4 is a section along line 4—4 in Fig. 3, 85 shown on an enlarged scale. Fig. 5 is the front view of a third combination of the same kind. Fig. 6 is a section along line 6—6 in Fig. 5, shown on an enlarged scale. Fig. 7 is the front view of a fourth combination of 90 this kind. Fig. 8 is a section along line 8—8 in Fig. 7, shown on an enlarged scale. Fig. 9 is the front view of a hinged double telescope and its support, a contrivance for altering 95 the angle between the two single tele- 100

scopes guiding also these telescopes upon, and symmetrically to, the support. Fig. 10 is a section along line 10—10 in Fig. 9, shown on an enlarged scale. Fig. 11 is the front 5 view of a similar combination. Fig. 12 is a section along line 12—12 in Fig. 11, shown on an enlarged scale. Fig. 13 is the front view of a third combination of this kind. Fig. 14 is the front view of a hinged double 10 telescope and its support, a balance spring being connected with a device which guides the two single telescopes upon, and symmetrically to, the support. Fig. 15 is the plan view of the middle part of a similar combination. Fig. 16 is a sectional front view corresponding to the plan view shown in Fig. 15.

In the arrangement according to Figs. 1 and 2 a handle *a* serves as support for the double telescope, provides rests for the single 20 telescopes by means of its two plates *a*¹, *a*² and guides the stud *b*⁰ arranged at the end of the hinge-bolt *b* by means of its slotted standard *a*⁰. In order to be able to detach the handle easily from the hinged double 25 telescope, the slot in the standard *a*⁰ at the lower end is made somewhat larger than the diameter of the head of the stud *b*⁰.

The support in the arrangement according to Figs. 3 and 4 is not detachable. It consists 30 principally of a hub *c*—carried by the hinge-bolt *b*—which is carried downwards to form a pivot *d* for insertion into a stand or the like, and upward into a guiding rod *c*⁰. The sleeve *e*, guided upon this rod, is connected 35 up by means of the links *e*¹, *e*² with the single telescopes.

The instrument shown in Figs. 5 and 6 is adapted to be detachable from the head *f* of a stand, which is here also equipped with a 40 pivot *d*. The head *f* carries the supporting arms *f*¹, *f*² provided with rollers and serves to guide the upright arm *g*⁰ of an angle piece, on the horizontal arm *g* of which the instrument with its hollow hinge-bolt *h* is pushed.

The arrangement according to Figs. 7 and 45 8 shows the instrument likewise detachable from the support, which is again represented as a stand head *i* with a pivot *d*. Its slotted standard *i*⁰ open at the top serves to guide 50 the sleeve *k*⁰ of the hinge-bolt *k*. Upon the arms *i*¹, *i*² of the stand head the single telescope rests with rollers *l*¹, *l*².

In the arrangement according to Figs. 9 and 10 the instrument proper is detachable 55 from the stand head *m*. The arms *m*¹, *m*² of the stand head are fixed hingewise to the stand head, and are altered by the aid of the right hand and left hand screws *n*¹, *n*² by means of its common nut *n*. The free ends 60 of the arms form four forked rests, in which the double telescope is laid with the pivots *o*¹, *o*².

The double telescope according to Figs. 11 and 12 is also detachable from the support.

The stand head *p* receives the head and neck 65 of the screw *q* in its slit *p*⁰ open at one side, said screw being provided with a hand wheel and gearing into the nut *q*⁰ revoluble upon the hinge-bolt *b*. The single telescopes rest upon the plates *p*¹, *p*² of the stand head. 70

The arrangement according to Fig. 13 shows the double telescope again undetachable from the stand head *r* in that this is pivoted upon the hinge-bolt *b*. The stand head serves as nut for a screw *s* provided with hand wheel, the said screw passing by means of a stud *s*⁰ through a tensile cord *t*¹ *t*², which connects the single telescopes. 75

The instrument Fig. 14 is permanently connected with the support and differs from 80 the double telescope, Figs. 3 and 4, principally through the intervention of a pressure spring *u* between the stand head *c* and the sleeve *e*.

The arrangement according to Figs. 15 and 16 is represented not only on a larger scale than the former examples (the single telescopes being broken off short), but it relates also to a hinged double telescope deviating 90 from the former in as far as on account of another position of the hinge the single telescopes are no longer inclined upward, but directed almost horizontally, in particular with the adjustment for the average inter-pupillary distance as represented stretched out in 95 a straight line. The instrument does not permit of being detached from the support, the stand head *v* again surrounding the hinge-bolt *b*. At the stand head, the outer end of a spiral spring *w* is attached, the inner 100 end of which is fastened to the hub of a double lever *x* pivoted on the head *v*. Upon this double lever and through that upon the spiral spring the moments of the weights of the single telescopes act by means of the pins 105 *y*¹, *y*². If the instrument be collapsed, a stop *v*⁰ on the head *v* prevents the spiral spring *w* turning the double lever *x* out of the paths of the pins *y*¹, *y*².

It will be understood, that in the combinations shown in Figs. 1 to 8 and 14 to 16 alteration of the angle between the single telescopes is effected by rotating at least one of these telescopes by hand. As to Figs. 14 to 16, the balance spring may either alone or in 115 combination with a suitable friction of the hinge secure the angle between the single telescopes; whereas in Figs. 9 to 13 the contrivance for altering that angle secures it also, and in Figs. 1 to 8 the friction of the 120 hinge serves alone to secure the angle, but of course such friction might be assisted or substituted by a special securing device.

I claim:

1. The combination with two single telescopes hinged together of a support therefor and a guide for keeping the telescopes symmetrical to the support. 125

2. The combination with two single telescopes hinged together of a support therefor and means for rotating the telescopes about the hinge symmetrically to the support.
- 5 3. The combination with two single telescopes hinged together of a support therefor, guiding means for keeping the telescopes symmetrical to the support and a balancing spring connected with the guiding means.

RUDOLF STRAUBEL.
